NOZZLE

Frank J. Rash, Chicago, Ill., assignor of one-half
to Elmer W. Barth, Chicago, Ill.

Application March 21, 1934, Serial No. 716,680

3 Claims. (Cl. 261—77)

This invention relates to injection circulators and more particularly to nozzles, although certain features thereof may be employed with equal advantage for other purposes.

It contemplates more especially the provision of means for injecting a medium such as steam into a system for effecting circulation throughout the interior of a tank thereby elevating the temperature of its contents incident to effecting thorough circulation without any appreciable accompanying noise.

Steam or other injecting mediums are commonly resorted to in breweries, laundries and similar enterprises where circulation within a tank is of importance in conjunction with temperature elevation of its contents. This injection is usually accomplished by substantial and deafening noises that prove troublesome and distracting to the attendants. Conversation between the attendants in necessary routine is almost impossible and work efficiency is, therefore, not as high as desirable or possible under such circumstances.

One object of the present invention is to simplify the structure and improve the operation of the devices of the character mentioned.

Another object is to provide a means for injecting a medium such as steam into a tank or other confining device to elevate the temperature of the contents as well as to effect the complete circulation thereof with minimum noise in consequence thereof.

Still another object is the provision of a simple nozzle to effect complete commingling of the contents within a confining tank incident to imparting an elevated temperature thereto without any appreciable noise.

A still further object is to provide a steam injector having means in association therewith for diffusing and guiding the medium therethrough without any appreciable noise.

Still a further object is to provide a nozzle having inclined apertures for directing the steam therethrough in conjunction with a conical tip disposed axially thereof for effecting the passage without any appreciable noise.

Other objects and advantages will appear from the following description of an illustrated embodiment of the invention.

In the drawing:

Figure 1 is a view in elevation of a beer tank having an injecting nozzle embodying features of the present invention.

Figure 2 is an enlarged fragmentary sectional view of the tank and the nozzle.

Figure 3 is a perspective view of the nozzle embodying features of the present invention and shown in association with the tank in Figures 1 and 2.

Figure 4 is an end view of the nozzle shown in Figure 3.

The structure selected for illustration comprises a tank 10 of any suitable configuration and designed for any purpose. In this instance, the tank 10 is of cylindrical configuration and of wooden construction; however, such may vary within a wide range depending upon the particular purpose for which it is employed or desired. In the case of a beer tank 10, the walls are reinforced by means of rods 11 having couplers 12 which are adjustable and in threaded connection with the extremities of the rods 11 to enable the tightening thereof from time to time.

This renders the tank 10 leak-proof and enables the maintenance thereof in such condition over extended periods. Steam coils 13 may be utilized in enveloping relation with the tank 10 so as to elevate the temperature thereof or to control such within commercial requirements for any desired purpose. The structure thus far described forms no part of the invention and merely serves to illustrate the purpose and manner of installation of a nozzle of the type embodying features of the present invention.

In its preferred embodiment, the nozzle comprises a tubular member 14 which terminates in a polygonal flange 15 for application to the interior wall of the tank 10. The interior surface of the member 14 is threaded as at 16 so as to be engaged by a pipe coupler 17 that has a correspondingly threaded extremity 18 serving as a complement thereof. The pipe member 17 is provided with a peripheral flange 19 that retains a gasket 20 in position against the interior wall of the tank 10 so as to be in hermetically sealed engagement therewith to direct the passage of steam or any other circulating medium therethrough. A supply of steam is directed to a pipe 21 in threaded engagement with the boss 22 of the flange 19, thereby directing steam to the interior of the tubular member 14 for injection within the interior 23 of the tank 10.

As shown, the tubular member 14 terminates in an enlarged tubular member 24 integrally or otherwise associated therewith to present a peripheral shoulder 25 beyond the confines of the tubular member 14. A rather thick wall 26 separates the interior of the tubular member 14 from the interior of the tubular member 24, there being a plurality of radially disposed and inclined

5 apertures 27, in this instance four, in the wall 26 to establish communication between the interiors of the tubular members 14 and 24. The apertures 27 are inclined, in this instance, at an angle of substantially 32° and diverge from the interior of the tubular member 14 to the interior of the tubular member 24 so as to diffuse the steam that issues therethrough.

10 In order to effect the passage of the steam through the tubular member 14 for injection within the interior 23 of the tank 10 without any appreciable noise which is an important factor, a conical tip 28 is formed axially of the apertures 27 and the base thereof extends substantially to 15 the entry orifices thereof so as to diffuse and guide the steam for passage therethrough with minimum noise. The tip 28 may be integrally formed in connection with the wall 26 but preferably comprises a detachable plug that has threaded shank 20 29 and a polygonal extremity 30 so as to extend through a correspondingly threaded aperture provided in the wall 26.

25 With this arrangement, the position of the conical tip 28 may be varied to effect the proper diffusion and passage of the steam with minimum noise and obstruction. So that the contents of the tank 10 may be circulated in consequence of the injection of the steam through the apertures 27, the peripheral shoulder 25 is provided with a plurality of apertures 31, in this instance four, that are curved to correspond with the configuration of the shoulder 25 and to comprise the largest possible area thereof so that the tank contents will 30 pass therethrough and establish circulation through the effort and urge imparted by the steam issuing through the apertures 27 for commingling with the tank contents. This affords proper circulation, mixing, temperature elevation, and such is effected with minimum noise characteristics 35 that are substantial and very annoying with the use of the customary injectors or nozzles.

40 Various changes may be made in the embodiment of the invention herein specifically described without departing from or sacrificing any 45 of the advantages of the invention as defined in the appended claims.

I claim:

1. In a device of the character described, the combination with a tubular member defining a passage, of an enlarged tubular member formed axially of said first named tubular member for attachment thereto to define a peripheral shoulder in spaced relation from the entrant orifice of said tubular member, there being openings in the peripheral face of said shoulder for enabling the

5 circulation of the surrounding medium, there being inclined apertures extending between said tubular members to establish communication for steam or other medium passage from one to the other, a conical tip extending axially within said first named tubular member to diffuse and direct the steam through said inclined apertures, and means for connecting a pipe line to the entrant orifice of said first named tubular member for directing the injecting medium through said inclined apertures to said enlarged tubular member.

10 2. In a device of the character described, the combination with a tubular member defining a passage, of an enlarged tubular member formed axially of said first named tubular member to 15 present a peripheral shoulder forwardly of the entrant orifice of said first named tubular member, there being inclined apertures extending between said tubular members to establish communication for steam or other medium passage from one to the other, there being apertures in 20 said shoulder for circulation of the surrounding medium therethrough responsive to said steam injection, an adjustable conical tip extending axially within said first named tubular member to 25 diffuse and direct the steam through said inclined apertures, and means for connecting a pipe line to the entrant orifice of said first named tubular member for directing the injecting medium through said inclined apertures to said 30 enlarged tubular member.

25 3. In a device of the character described, the combination with a tubular member defining a passage, of an enlarged tubular member formed axially of said first named tubular member to 35 present a peripheral shoulder forwardly of the entrant orifice of said first named tubular member, there being inclined apertures extending between said tubular members to establish communication for steam or other medium passage from one to the other, there being circumferentially spaced apertures in said shoulder for circulation of the surrounding medium therethrough responsive to said steam injection, a conical plug 40 having a threaded shank for axial engagement with said first named tubular member centrally of said inclined apertures to diffuse and direct the steam therethrough, and means for connecting a pipe line to the entrant orifice of said first 45 named tubular member for directing the injecting medium through said inclined apertures to said enlarged tubular member.
